UNITED STATES PATENT OFFICE.

FRANK RYCHLEWSKI, OF CHICAGO, ILLINOIS, ASSIGNOR, BY MESNE ASSIGNMENTS, TO THE GERRARD COMPANY, INC., OF SAN FRANCISCO, CALIFORNIA, A CORPORATION OF DELAWARE.

TENSION DEVICE FOR WIRE-TYING MACHINES.

Application filed February 26, 1925. Serial No. 11,631.

This invention is a tension device for wire-tying machines, the object being to provide for the free initial introduction of a wire tie and, by a rotative movement of a tension member, to effect a self locking engagement between said member and the tie whereby tension is placed on the tie by a further rotative movement of the member.

In my invention the tension mechanism includes a body member, and a tie-retaining member or dog, so related to each other that a wire-receiving space is produced the dimensions of which exceed the normal diameter of the wire, whereby the tie may be inserted initially with ease and freedom, and, by a rotative movement of the body member, the relation of the body member and of the tie-retaining member or dog are changed to the end that the tie itself is locked or held against endwise movement with respect to both the dog and the body member, thus making provision for tensioning the tie by a further rotative movement of the body member.

In a practical form, the body member is a head provided with an abutment, and the tie-retaining member is a dog which is carried by the head so as to be movable therewith and which dog is rotatable with respect to the head for co-operation with the abutment in producing a space or opening for the reception of the wire tie. This space or opening exceeds the normal diameter of the wire composing the tie, and to this end, yieldable means are provided for retaining the body member and the tie-retaining member in such relation to each other as to permit the free and unobstructed insertion of an end portion of the tie, such introduction of the wire end being effected by either an endwise movement or by a lateral movement of the tie with respect to the head. With the end portion of the tie introduced initially, the body member is turned a certain angular distance for bending the tie in order to position said tie with respect to the parts of the tying machine, and in this bending operation the pressure or resistance of the tie so acts upon the dog as to turn it relatively to the body member or head, and thus overcome the yieldable means, with the result that the dog and the abutment are adapted to so engage with the tie as to anchor the tie within, or lock it to, the head,

and finally a further rotative movement of the head or body member places the required tension on the tie, the latter being retained in non-slipping engagement with the head during the tensioning operation. In this connection it is to be noted that the dog is under the influence of the yieldable means (usually a spring) for retaining said dog normally in a position to produce the space which exceeds the normal diameter of the wire, and, further, the tension device is usually provided with a plurality of dogs, in which event a single spring is ordinarily provided for retaining said dogs in place, to the end that at each dog there is a wire-receiving space the width of which exceeds the normal diameter of the wire.

My invention is or may be used in connection with plain round wire, but it is useful, more particularly, with deformed wire ties, an example of which is disclosed in Cary's United States Patent No. 1,419,110, patented June 6, 1922.

Other functions and advantages of the invention will appear from the following description taken in connection with the drawings, wherein—

Figure 1 is a side elevation of one kind of wire tying machine with which my tension device may be used, said tension device being shown in position for initially receiving an end portion of a deformed wire tie.

Figure 2 is a side elevation of the tension device turned to a position wherein the deformed tie is locked to or anchored in position between one dog and one abutment of the rotatable head or body member, a part only of the tying machine being shown.

Figure 3 is an elevation of the head or body member looking at the opposite side from Figures 1 and 2.

Figure 4 is a cross section on the line 4—4 of Figure 2.

Figure 5 is a plan view of the head or body member, and

Figure 6 is a perspective view of the tie-locking dog.

A is the body member or head and B the dog or dogs carried by said head and rotatable therewith for placing under tension a wire tie adapted by the operation of the tying machine, shown partly in Figures 1 and 2, to be drawn tightly into contact with

an object and to be fastened securely in position, whereby the tie may be expeditiously put on the object and be applied so securely thereto that it cannot be dislodged and will 5 serve efficiently in binding the object and increase the stability thereof.

The body member or head is composed, preferably, of a single piece of metal, and on one face thereof said head is formed 10 with a plurality or series of abutments *a*, whereas on the other face the head is provided with ratchet teeth *a'*, and, further, the peripheral surface of the head is knurled or roughened, as at *a*². The head is bored or 15 drilled to provide an axial opening *c*, and said head is, furthermore, bored or drilled to produce a circular row of openings *d* for the accommodation of the series of dogs *B*, the number of which is optional.

20 In the production of the head, one face thereof, i. e., the outer face, is cut usually by milling operations to remove the metal in lines radial to the axis of the head and result in the formation of radial recesses *C* 25 which produce the abutments *a*, and by further operations these abutments are cut away to ultimately impart the more or less irregular formation to the abutments shown more particularly in Figures 1 and 2. Each 30 abutment is a five sided figure, with sides *e*, *f*, radial to the axis of the head, a side *g* at an angle to the side *f*, an inner curved edge *h*, and an outer curved edge *i*, the curved edges *h*, *i*, being concentric with the axis of 35 the head. The radial recesses *C* are enlarged at their outer ends by the provision of the inclined edges *g* on the abutments, *a*, and these enlarged ends of the radial recesses allow for the free introduction of the 40 wire tie, *D*, which, when thrust by an endwise movement, may strike or slide against the inclined edges *g* of one of the abutments *a*, and thus be directed into a position for engagement with one abutment and a dog *B* 45 co-operable with said abutment. The short curved edge *h* at the inner narrow end of the abutment joins with the longer of the two radial edges of the said abutment to form a shoulder *E* at an inner corner of the 50 abutment, and this curved edge *h* is undercut to produce a recess indicated by dotted lines in Figures 1 and 2, and thus form a narrow lip *j* at the edge, see Figure 4, the utility of which will presently appear. The 55 circular row of openings *d* are formed in the head *A* in such positions that one boundary edge of each opening *d* is in a plane which crosses the longer radial edge *e* of one of the abutments, see dotted lines in 60 Figures 1 and 2, and thus the abutments *a* of the head are adapted to serve as stops for limiting the endwise play in an outward direction of the dogs *B*.

Each dog *B* is shown as a cylindrical stem 65 the end portions of which are cut away, see

Figure 6. The diameter of the dog in the body portion thereof is equal, nearly, to the diameter of a hole *d*, to the end that the dog fits easily within the hole and is free to turn axially thereon. At the outer end, the 70 dog is cut away to form a flat face *k*, and a narrow lip *k'*, the latter being in the same plane as the lips *j* on the edges *h* of the abutments, whereby the lips *j*, *k'*, of the abutments and the dogs tend to present displacement in a sidewise direction of the inserted deformed end portion of the tie *D*.

The other (or inner) end portion of each dog *B* is cut away to produce a flat face *l* at said inner end, the cut away portion at the inner end being in a direction at an angle to the cut away portion at the outer end, see Figure 6, and thus the flat face *l* at the inner end is at an angle to the flat face *k* at the outer end of said dog.

The dogs *B* are journaled in the holes *d* of the head for the cut away ends to enter the radial recesses *C* of said head, and thus the flat-faced end portions *k* of the dogs occupy positions opposite the shouldered inner ends *E* of the abutments *a*, whereby the dogs and the shoulders *E* are positioned in co-operative relation to each other. Said shoulders *E* of the abutments and the cut away ends of the dogs are on opposite sides, respectively, of the path of a deformed end *D'* of the tie *D* when the latter is inserted within a recess *C* of the head, and thus the shoulder *E* is adapted for engagement with a shoulder on one side of the deformation *D'*, whereas the edge of the flat face *k* of the dog is adapted for engagement with another shoulder on the opposite side of the deformation *D'* of said wire tie, see Figures 1 and 2, the result of which relation is to bring about a locking engagement of the shoulder *E* and the dog with the respective sides of the deformed tie *D* in a manner to hold the tie against endwise movement relatively to the head *A* in the operation of said head for placing tension on said tie.

The inner face of the head is provided with a channel or groove *m*, see Figures 3 and 4, said groove being inside of the ratchet teeth *a'* and concentric with the axis of the head. The inner cut away ends of the dogs *B* extend across the groove *m*, and within this groove is encased a spring *F*, the latter engaging with the flat faces *l* at said inner ends of the dogs, see Figures 3 and 4. The spring *F* is a split ring of sufficient spring power to act on the dogs *B* of the series, and thus a single spring is common to the series of dogs instead of employing as many springs as there are dogs, thus simplifying the construction.

The spring performs an important function in my tension head, i. e., it acts to place tension on all the dogs, and it acts to retain each dog in a position wherein the flat face

k of the dog is parallel, or substantially parallel, to the radial edge *e* of the abutment, see Figures 1 and 2. This relation of the dogs to the abutments produces a series 5 of tie-receiving spaces in the head, each tie-receiving space being of a width which slightly exceeds the normal diameter of the tie, and thus the tie may be introduced freely and easily into such a space, and at any 10 one of a number of such spaces in the head, depending, however, upon the position of said head with reference to the other working parts of the tying machine.

In my device with the tie-receiving spaces 15 of a width exceeding the normal diameter of the tie, it is possible to introduce the deformed end *D'* of said tie by moving the wire endwise through the recesses *C*, or by moving the deformed end *D'* of the tie laterally in a direction sidewise of the head, but in either mode of inserting the tie (endwise or sidewise), the shouldered portion at 20 said deformed end passes into or within the tie-receiving space easily because the width 25 of this space exceeds the normal diameter of the tie, the spring *F* acting on the dogs for holding the latter at all times under tension and each dog being pressed by the spring to a position wherein the flat face *k* 30 of the dog is parallel, or substantially so, with a straight side edge *e* of the abutment.

The mode of using the tension device is to introduce with one hand the deformed end *D'* of the tie into the space between one 35 abutment and one dog, substantially as shown in Figure 1, whereupon the operator grasps with the other hand the knurled edge *a'* of the head, and forcibly turns said head from the position of Figure 1 to the position 40 of Figure 2. This partial rotation of the head bends the tie and deflects it from the straight position of Figure 1 to the angularly bent condition of Figure 2, and at this operation the pressure placed on the 45 wire by the partial rotation of the head reacts on the flat face *k* of the dog *B*, with the result that the dog is partially rotated in the bearing *d* of the head, thus overcoming the annular spring *F*. By the described 50 operation, the dog *B* is turned so that an edge of the face *k* takes behind or engages with a shoulder on the deformed end *D'* of the wire tie, and said deformed tie end is forcibly thrust against the shoulder *E* of 55 the abutment *a* adjacent to the dog, whereby two shoulders on the deformed tie end are engaged by the shoulder *E* and by the dog, respectively, with the result that the deformation of the tie is locked to, or anchored 60 within, the tension head. This partial rotation of the head *B* by hand automatically anchors the deformed tie to the head, and also bends the tie and depresses said tie into a position where said bent tie may be 65 trained or deflected around a direction roller

G of the tying machine, thus enabling the tie to be manipulated by hand in a manner to loop the tie around a package and to dispose said tie relatively to the tying machine for the performance of the operations of 70 placing tension on said tie and of joining the end portions of the tie loop, usually by twisting said end portions.

The tying machine shown in Figure 1 and partly illustrated in Figure 2 embodies a 75 suitable base or frame *H* provided with a tie-receiving slot *n*, a tension lever *I*, a shaft *J*, a slotted twister pinion *K*, shown by dotted lines in Figure 1, and a gear *K'* meshing with said twister pinion and operated 80 by a lever (not shown) independently of the lever *I*. The lever *I* is provided with a pawl (not shown in this application), adapted for engagement with a tooth *a'* of the ratchet formation; and after the wire tie 85 shall have been introduced in the head *A* and said head partially turned by hand to the position of Figure 2, and also after the wire is trained around the package as mentioned, then the operator pulls on the lever 90 *I* to further rotate the head *A*, the effect of which is to pull on the wire *D* and place the required tension thereon, whereupon the gear *K'* is operated by the other independent lever for the purpose of rotating the 95 pinion *K* and thereby join the ends of the wire loop by intertwisting said ends.

In the operation of placing tension on the tie by the further movement of the head *A* under the action of lever *I*, the tie is in contact with the peripheral surface of the head *A*, and to direct the wire as well as retain it in position on this surface, the outer curved faces *i* of the abutments are provided with a peripheral groove *i'* into which the wire is received when partially wrapped around head *A* in such tensioning operation.

The head *A* is carried by the machine shaft *J*, for which purpose the shaft is received in the axial shaft opening *c* provided in the head. This head is mounted loosely on the shaft to the end that the head may be turned freely by hand in the operation of anchoring or attaching the tie to said head, 110 but the head *A* is connected operatively with the tension lever *I* by the pawl in engagement with the ratchet tooth *a'*, whereby the head operates independently of the lever and is adapted for operation by said lever. 115

As shown, the end portion of the shaft *J* is reduced in diameter to produce an axially positioned pin *J'*. Said pin extends into the space between the abutments *a* and the dogs *B*, and it is in line radially with the tie-receiving spaces between said abutments and the dogs, as a result of which the pin is in the path of the tie when inserted and thus performs the function of a stop to limit the initial introduction of the tie, as shown in 120 125 130

Figure 1. The stop J' arrests the inward movement of a tie when inserted in any one of the series of tie-receiving spaces, and aids the operator in positioning the tie relatively to the head, for the reason that the stop arrests the wire when shoved endwise and thus the wire is positioned for the shoulder E and dog B to have engagement with the shoulders of said deformed tie, see Figure 2.

10 In the operation of turning the head A by hand following the introduction of the tie, and of bending the wire around the roller G, the wire may have a tendency to slip sidewise relatively to the abutment a and the 15 dog B, but the lip j k' on the abutment and the dog, respectively, arrest this sidewise dislodgment of the tie and prevents said tie from slipping out of position with reference to the tie-engaging elements a, B, of said 20 tension head.

Having thus fully described the invention what I claim as new and desire to secure by Letters Patent is:

1. A tie-tensioning element for wire tying 25 machines embodying a head, and a plurality of co-operating tie-engaging members carried by said head, said tie-engaging members being relatively separated by an interval which exceeds the normal diameter of a wire 30 tie adapted to be inserted therein, said tie-engaging members being operable by the movement of said head for bending an inserted wire tie the resistance of which acts on said members to effect a gripping engagement between said members and said wire tie.

2. A tensioning device for wire tying, embodying a head provided with a tie-engaging member, a second tie-engaging member 40 movable relatively to the first-named member and cooperable therewith in producing a tie-receiving space, and means operable for holding the second member in spaced relation to the first member, said head being 45 movable bodily for bending an inserted wire tie and for effecting a gripping engagement by said two named members with said tie adapted to be inserted into said tie-receiving space.

50 3. A tensioning device for wire tying machines embodying a head provided with a tie-engaging member, a second tie-engaging member carried by said head and movable relatively to the first named member for engagement with a tie, and means operating on the second member for retaining the latter in a separated relation to the first member and producing a tie-receiving space between said members, said head being rotatable at will and acting on an inserted wire tie for bending said tie, the resistance of which shifts the second member into gripping contact with said tie.

4. A tensioning device for wire tying embodying a head provided with a tie-engag-

ing member, a second tie-engaging member mounted in said head in co-operative relation to the first named member, said second named member being movable relatively to the first named member and producing therewith a tie-receiving space the width of which exceeds the normal diameter of a wire tie adapted to be introduced into said space, and yieldable means operable on the second named member for retaining the latter normally in a separated relation with reference to the first named member, said first and second members being operable by a movement of said head for bending an inserted wire tie the resistance of which moves the second member to effect a gripping engagement between the two members and the inserted wire tie.

5. A tensioning device for wire tying embodying a head provided with a tie-engaging member, a second tie-engaging member carried by the head and positioned in cooperative relation to the first named member to produce a tie-receiving space which is open laterally of the head, and means on said tie-engaging members for precluding dislodgment of a wire tie in a sidewise direction when introduced into said tie-receiving space, said first and second tie-engaging members co-operating by a movement of said head to bend an inserted tie the resistance of which acts to effect a gripping engagement of said members with the inserted tie.

6. A tensioning device for wire tying embodying a head provided with a plurality of tie-engaging members, a plurality of other tie-engaging members carried by said head and each positioned in co-operative relation to one of the first named members for producing therewith a tie-receiving space which is open laterally of the head for the sidewise insertion of a wire tie between the co-operable tie-engaging members, and spring mechanism co-operable with said second named tie-engaging members for holding the latter in a separated relation to the first named members, said first and second tie-engaging members co-operating by a movement of said head to bend an inserted tie the resistance of which acts to effect a gripping engagement of said members with the inserted tie.

7. A tensioning device for wire tying embodying a head provided with two series of tie-engaging members positioned to produce a series of tie-receiving spaces which are radial to the axis of the head and each of which spaces is open laterally of the head, and means co-operating with substantially all of said head and with the tie-engaging members for holding said tie-engaging members normally in separated relation and thereby permit the introduction of a wire tie into either of said tie-receiving spaces,

- the co-operating tie-engaging members acting to bend an inserted wire tie the resistance of which shifts said members relatively for effecting a gripping engagement of said members with the inserted tie. 5
8. A tensioning device for wire tying embodying a rotatable head, two series of tie-engaging members carried thereby and relatively positioned to produce tie-receiving spaces extending radially to the axis of the head, and means co-operating with said tie-engaging members for retaining the same in separated relation, said head being rotatable at will for deflecting an inserted wire tie and shifting one of said tie-engaging members with respect to its complementary member for effecting a gripping engagement of said two named members with an inserted wire tie, the co-operating tie-engaging members acting to bend an inserted wire tie the resistance of which shifts said members relatively for effecting a gripping engagement of said members with the inserted tie. 10
9. A tensioning device for wire tying embodying a head provided with a plurality of substantially radial members in fixed relation to said head, a plurality of movable members co-operable with the first named members to produce therewith a succession of tie-receiving spaces extending substantially radially to the head, and a spring co-operating with said movable members for yieldably retaining the latter in a predetermined relation to the fixed members. 15
10. A tensioning device for wire tying embodying a head provided with two series of co-operable tie-engaging members relatively separated from each other and producing tie-receiving spaces extending substantially radially of the head, and a tie-stop positioned substantially centrally of the head for arresting the inward movement of a tie adapted to be introduced into one or the other of said tie-receiving spaces. 20
11. A tensioning device for wire tying embodying a head provided with a plurality of tie-engaging abutments, a plurality of dogs rotatably mounted in said head, each dog having a substantially flat face co-operable with one of said abutments, and a spring device operating on the dogs for retaining the flat faces thereof in a separated relation to the abutments and thereby producing tie-receiving spaces extending substantially radially to the head. 25
12. A tensioning device for wire tying, embodying a head provided on one face with a plurality of tie-engaging members and in its opposite face with a groove, a plurality of dogs co-operating with tie-engaging members, said dogs having flattened portions adjacent said groove, and a spring occupying the groove and contacting with said flattened faces of the dogs for placing tension thereon. 30
13. A tensioning device for wire tying embodying a head provided with a plurality of tie-engaging means in fixed relation thereto, a plurality of movable tie-engaging members each co-operable with one of said fixed tie-engaging members, and yieldable means for holding each movable tie-engaging member in separated relation to its complementary tie-engaging member, said head being rotatable at will for imparting movement to the fixed tie-engaging member whereby the latter acts on an inserted tie wire to press it against the complementary movable tie-engaging member and thereby effect a locking engagement of the complementary members with an inserted wire tie. 35

In testimony whereof I have hereto signed my name this 19th day of February, 1925.

FRANK RYCHLEWSKI.
